AUTOMATIC FIREARM, IN PARTICULAR
MACHINE GUN

Václav Holek, Brunn, Czechoslovakia, assignor to
firm Ceskoslovenska Zbrojovka akciová spole-
nost v Brne, Brunn, Czechoslovakia

Application March 1, 1934, Serial No. 713,483
In Great Britain March 15, 1933

13 Claims. (Cl. 42—3)

The present invention relates to an automatic firearm and more particularly to a machine gun which operates on the gas pressure loading principle, that is to say a firearm in which the gases of discharge are made use of to drive the breech lock mechanism.

It is already known to provide many kinds of firearms, including gas-operated guns, with a resilient butt-plate in order to damp the recoil shocks produced by the discharge. In such an arrangement, however, the mass which moves in response to the discharge is very great and, therefore, the recoil against the shoulder of the user is considerable.

Various arrangements for damping recoil shocks have also been proposed in connection with firearms other than gas-operated guns.

For instance, it has been proposed to provide resilient damping means between a firearm and an adjustable shoulder support.

It has also been proposed to provide a gun with telescopic stock, the parts being normally kept in their extended position by a spring which is compressed by the recoil on discharge thus storing the energy necessary for forcing the next cartridge into the barrel and for closing the breech.

It has further been proposed to construct a gun for firing signal rockets and the like in two main parts, namely a fixed part and a movable part, connected by a resilient telescopic damping device, the gun stock, gun frame, trigger and trigger bar being comprised in the fixed part in which the movable part, comprising the barrel and the firing mechanism (excluding the trigger and trigger bar), is adapted to slide longitudinally.

The object of the present invention is to provide a gas operated gun in which the recoil shocks caused by the firing of a shot are damped within the firearm itself, without substantial alteration in the manner of construction of the firearm. The gun is composed only of such parts as are found in existing gas operated guns.

According to the present invention this object is attained in that the firing mechanism of the firearm, together with the firing casing and the part adjoining it form one unit and the breech lock casing, together with the barrel and the gas pressure motor form a second unit, the second unit being so connected for longitudinal movement with the first mentioned unit that the second unit can perform a recoil movement when a shot is fired.

A light machine gun is illustrated in the ac-

companying drawings as a constructional example of the invention.

Fig. 1 shows the machine gun in longitudinal section in the rest position.

Fig. 2 shows the machine gun in partial longitudinal section, after a shot has been fired, with the breech block mechanism and the breech block casing occupying the rearward position.

Fig. 3 shows the firearm in the rest position in side elevation.

Fig. 4 shows on an enlarged scale a longitudinal section through the rear part of the breech block casing.

Fig. 5 is a section on line V—V of Fig. 4 as viewed from right to left.

Fig. 6 shows a section on line VI—VI of Fig. 1 on an enlarged scale.

Fig. 7 is a cross section on line VII—VII of Fig. 1 on an enlarged scale, but only through the casing of the trigger mechanism.

Fig. 8 is a section on line VIII—VIII of Fig. 1 on an enlarged scale.

The shock absorbing device is illustrated in Figs. 9 and 10.

Fig. 9 shows the device in partial longitudinal section and

Fig. 10 is a front elevation of the device.

1 is the barrel, 2 is the casing of the breech block mechanism or the "breech block casing", 3 is the gas junction, 4 is the gas pressure cylinder, and 5 is the gas pressure piston. The piston rod of the gas pressure piston 5 carries the breech block mechanism which, in the present constructional example, consists of the breech block carrier 6 and of the breech block 7 which rocks towards and away from the breech block carrier. 8 is the firing pin provided in the breech block and 9 is the tooth provided on the casing 2 and adapted to lock the breech block 7.

In the breech block carrier 6 is provided a recess 10 which co-operates with the tooth of the two-armed sear 12. A spring 14 abuts against one arm of the sear 12 and in the other arm is provided in a known manner a recess with which co-operates the trigger bar 15, which in turn can be operated by the trigger 17. 16 is the switch member for setting the firearm for firing single shots and for continuous fire, as well as for safety.

The firing mechanism is mounted in the firing casing 20; the latter is provided with a cartridge ejection opening 22 and with a handle 18.

In the rear wall of the firing casing 20 is secured the butt 32. 33 is a spring passing through a tube in the butt and adapted to urge forward

10 screwed over the end of the tube 40 also serves
15 for securing the butt 32 to the firing casing 20,
as shown in Fig. 1.
The firing mechanism 12, 14, 15, 16, 17 of the
20 firearm together with the firing casing 20 and
the butt 32 secured thereto form one unit x. The
25 breech block casing 2, together with the barrel
1 and the gas pressure motor 4, 5 form a sec-
ond unit y. The second unit y is so connected
30 for longitudinal movement with respect to the
unit x that when a shot is fired the second unit
can carry out a recoil movement. The breech
block casing 2 is formed with an opening 62
35 parallel to its path of movement (Fig. 5). The
unit x is movably guided within this opening and
the firing casing 20 is constructed as a closing
member for the opening. In the above described
40 constructional example the breech block casing
2 has a box shaped cross section. The box shaped
breech block casing is open on one side at the
opening 62 and the missing side of the breech
45 block casing is formed by the firing casing 20
(Fig. 8). In order to guide the unit y with re-
spect to the unit x the breech block casing is
provided with guide grooves 24 and the firing
casing 20 with guide projections 23. In addition
45 to this guide provided along the opening 62 the
unit y is further guided with respect to the unit
x by a support separate from the guide means 23,
24. This support consists of a pin 28 on the cas-
ing 2 which passes through an elongated slot
29 in the firing casing 20.

The firearm is provided with an arrangement
which stores energy during rearward movement
45 of the breech block casing and liberates energy
during forward movement of the breech block
casing, and at the same time acts as a shock ab-
sorber for the breech block mechanism by acting
upon the breech block carrier 6.

The arrangement which liberates energy con-
50 sists, in the present constructional example, of a
spring controlled piston 48 which is constructed
with abutments 49 for the breech block casing.
The abutments are, in the present constructional
55 example, formed as wings, which engage in re-
cesses 26 in the breech block casing 2 (Figs. 4
and 5). The parts 49, 26 form a coupling which
operates in one direction between the piston 48
60 and the breech block casing. This is of impor-
tance, since the spring loaded piston 48 has not
only to serve for guiding the breech block cas-
ing 2 rearwardly but also forms a shock absorber
for the breech block carrier 6. The piston 48
65 must be able to carry out both functions inde-
pendently of one another and this is only pos-
sible if there is located between the piston 48
and the breech block casing 2 a coupling which
operates in one direction. The piston 48 is se-
cured against rotation by guide means 53, 54
70 consisting of a wing 53 which engages in a suit-
able recess 54 in the casing 20. The spring load-
ed piston 48 is hollow and the parts 34, 40 of the
advancing device extend through its hollow in-
terior 48'. 43 is the spring which acts upon the
75 piston 48 and abuts with its rear end against

the intermediate piece 49 secured to the
piston 48. The forward end of the spring 43 10
abuts against the ring 48.

Fig. 2 shows in one and the same figure dif-
ferent parts in the positions which they occupy
during two consecutive phases in the cycle of
operations of the firearm, namely, the position of y
15 of the unit y directly after a shot has been fired
and the position of the breech block mechanism
a moment later when the shot has just left the
barrel. The sequence of operations of these parts
is as follows: When firing a shot the unit y 20
moves rearwardly over the short distance z, with
the result that the abutments 26a (Fig. 4) im-
pinge on the wings 49 of the piston 48, move
the piston 48 rearwardly and, by compressing the
25 spring 43, charge the latter with the kinetic en-
ergy of the unit y. Meanwhile the shot will have
been driven back, carrying with it the breech
block mechanism. The rearward travel of the
30 breech block mechanism is many times greater
than the distance z and, consequently, the pis-
ton 48 and the unit y will have been returned by
the shock absorbing spring 43 into the positions
35 illustrated in Fig. 1 before the breech block mech-
anism has completed its rearward travel. The
breech block carrier will therefore impinge upon
the piston 48 and the resilient arrangement will
40 operate as a shock absorber for the breech block
mechanism. Thus the shock absorbing spring
43 is not only charged with the kinetic energy of
the breech block mechanism during the last part
45 of the rearward movement but also with the
kinetic energy of the unit y, since the breech
block casing 2 is connected with the spring load-
ed piston 48 through the abutment 26 and the
wing 49.

After the rearward movement is ended the
unit y is carried forward by the shock absorbing
50 spring 43 into the starting position. The breech
block mechanism is driven forward by the ad-
vancing spring 33 and its movements are regu-
lated by the firing mechanism which can be
adjusted in a known manner by means of the
55 switch member 16 for firing single shots or for
continuous fire or can be secured against tri-
pping of the sear.

After the last cartridge has been fired from
the magazine 51 the breech block 7 is held fast
in known manner in the rearmost position by the
feed device located in the magazine 51 which 60
protrudes in the path of movement of the breech
block. After removal of the empty magazine
the breech block carrier 6 is held back in the
tensioned position by the tooth of the sear 12.

The distance between the first cartridge of the
65 newly inserted magazine and the front surface
of the breech block 7 is increased by the forward
movement of the unit y, so that, upon the sub-
sequent pressing of the trigger 17, the breech
block mechanism 6, 7 thus freed strikes against
70 the first cartridge of the new magazine with
greater kinetic energy. This will insure an ac-
curate and definite sliding of the cartridge out
of the magazine, the sliding of the cartridge
75 into the firing chamber, and the locking of the

breech block mechanism. The greater readiness in firing thus obtained results, without the addition of an auxiliary member, merely from the suitable utilization of the shock absorbing spring 43, which in known firearms is used only to nullify the recoil shock of the breech block mechanism, but is here used also to damp the movement of the unit y . By providing the unit y with a spring, the recoil shock occurring upon each shot is absorbed by the shock absorbing spring 43, so that a soldier firing the gun would suffer no shocks which might affect the quality of the firing.

The assembling and dismantling of the above described firearm can be quickly and easily carried out. The two casings 2 and 22 are disconnected by withdrawing the pin 28. The casing 2, together with the parts of the firearm mounted on it can next be removed from the casing 20. Thus access may be had to the firing mechanism and also to the breech block mechanism. The advantage of easy dismantling of the firearm is of considerable importance in adjusting the operation of the gun and in replacing damaged parts.

The firearm described above and illustrated in the accompanying drawings represents only one constructional example of the invention which may be altered within the scope of the invention defined in the claims.

I claim:

1. In an automatic gas pressure loading firearm, a firing mechanism, a firing casing, a butt adjoining the firing casing, said mechanism, casing and butt forming a first unit, a barrel, a breech block casing fixed to said barrel, a gas pressure cylinder in connection with said barrel, a recoiling breech block mechanism slidably guided in said breech block casing, a gas pressure piston arranged in said gas pressure cylinder and operatively connected with said breech block mechanism, said barrel, breech block casing, cylinder, breech block mechanism and piston forming a second unit, and guiding means carried by said units, respectively, to slidably guide said second unit longitudinally with respect to said first unit for a recoil movement over a distance substantially shorter than the recoil path of the breech block mechanism in the breech block casing.

2. In an automatic gas pressure loading firearm, a firing mechanism, a firing casing, a butt adjoining the firing casing, said mechanism, casing and butt forming a first unit, a barrel, a breech block casing fixed to said barrel, a gas pressure cylinder in connection with said barrel, a recoiling breech block mechanism slidably guided in said breech block casing, a gas pressure piston arranged in said gas pressure cylinder and operatively connected with said breech block mechanism, said barrel, breech block casing, cylinder, breech block mechanism and piston forming a second unit, guiding means carried by said units, respectively, to slidably guide said second unit longitudinally with respect to said first unit for a recoil movement over a distance substan-

tially shorter than the recoil path of the breech block mechanism in the breech block casing, a device storing energy during the rearward movement of the breech block casing and means for imparting the energy to the breech block casing during its forward movement, said device constituting a shock absorber for the breech block mechanism.

3. Automatic firearm as claimed in claim 1, and in which the breech block casing has an opening extending parallel to its direction of movement, and a guide within said opening for said first unit.

4. Automatic firearm as claimed in claim 1 and in which said breech block casing is box-shaped and is open on one side, said firing casing being slidably guided within said open side.

5. A device according to claim 2 and a one-way coupling loosely connecting said device to the breech block casing.

6. Automatic firearm as claimed in claim 2, said device comprising a spring loaded piston, and abutments on said piston connecting the latter to the breech block casing.

7. Automatic firearm as claimed in claim 2, said device comprising a spring loaded piston, and means for connecting said piston to the breech block casing said means comprising wings on said piston engaging in recesses of the breech block casing.

8. Automatic firearm as claimed in claim 2, and in which said device comprises a spring loaded piston having abutments for connecting said piston to the breech block mechanism and casing, and guide means for securing said piston against rotation.

9. Automatic firearm as claimed in claim 2, and in which said device comprises a spring loaded hollow piston having abutments for connecting said piston to the breech block mechanism and casing, and a rod extending through said hollow piston and engageable with the breech block mechanism to advance the latter.

10. Automatic firearm as claimed in claim 2, and a friction brake cooperable with said device.

11. Automatic firearm as claimed in claim 2, and a friction brake cooperable with said device, said brake comprising a slotted spring ring and a control coating with said ring to convert axial forces into radially expanding forces.

12. In an automatic firearm, the combination with the elements claimed in claim 1, of means for guiding said units in their relative movement, said means including guide grooves in the breech block casing and guide projections carried by the firing casing and slidably in said grooves.

13. In an automatic firearm, the combination with the elements claimed in claim 1, of means for guiding said units in their relative movement, said means including a slot and pin connection between said units, guide grooves in the breech block casing and guide projections carried by the firing casing and slidably in said grooves.

VÁCLAV HOLEK. 65
